UNITED STATES PATENT OFFICE.

CHARLES F. J. DUPUY, OF NEW YORK, N. Y., ASSIGNOR TO CHANNELL CHEMICAL COMPANY, OF CHICAGO, ILLINOIS, A CORPORATION OF ILLINOIS.

DUST-MOP.

1,192,047.

Specification of Letters Patent. Patented July 25, 1916.

Application filed March 17, 1914, Serial No. 825,264. Renewed December 17, 1915. Serial No. 67,486.

To all whom it may concern:

Be it known that I, CHARLES F. J. DUPUY, a subject of the King of Great Britain, and a resident of the city of New York, borough of Manhattan, in the county and State of New York, have invented a new and Improved Dust-Mop, of which the following is a full, clear, and exact description.

Among the principal objects which the 10 present invention has in view are: to provide a mop of the character disclosed with means whereby is avoided marring the standing trim and furniture of a room; to provide a mop constructed to permit washing and cleaning by manipulating the same; to provide a forming block arranged to hold the mop in service condition; to provide a 15 mop constructed to permit polishing therewith; to provide a mounting for the mop, 20 which is simple and easy of operation and positive in its action; and to provide a construction which is relatively cheap.

Drawings.—Figure 1 is a vertical section of a mop constructed and arranged in accordance with the present invention, the section being taken on the line 1—1 in Fig. 2; Fig. 2 is a horizontal section taken on the line 2—2 in Fig. 1; Fig. 3 is a perspective view of a mounting block used in connection with the present invention; Fig. 4 is a 30 perspective view of a mop constructed and arranged in accordance with the present invention.

Description.—In the assembled or service 35 condition of the mop, a block 9 is inserted within the pocket of a mitt 10. The block 9 is shaped to fit the mitt, and has a groove 11 formed in the forward and side edges thereof. The groove 11 is shaped to hold 40 a binder or girdle 12. The girdle 12 is contained within the pocket of the mitt 10, the edges of the top of said mitt being folded over the sides of the block 9 and there stitched or otherwise secured. The edge of 45 the bottom or under side of said mitt is overturned to form an edging which is laid against the inner side of said girdle, and the superposed layers of the girdle and of the top side and under side of said mitt are 50 stitched or sewed together, thus completely covering the block.

The mop proper is constructed from

fringed material arranged to form a hollow-centered ring 13. The ends of the material forming the ring 13 are imprisoned between 55 the sides of the girdle 12. The girdle 12 thus forms a binder for the fringed material, and is constructed from canvas or other suitable material to permit the girdle to be pulled to tightly grip the block 9. The 60 girdle 12 being used to grip the block, it is provided adjacent each end with metal eyelets 14. The eyelets 14 are provided to receive fingers 15, which are pivotally mounted by pins 16 in a channel frame 17. The 65 channel frame 17 has mounted thereon a double-ended flat spring 20. To mount the spring 20, I provide a short post 18 and a screw 19. The frame 17 is held in the block by wood-screws 21, as seen best in Fig. 2 70 of the drawings.

The fingers 15 are each provided with a toe 22 and a heel adjacent the pins 16. The free ends of the fingers are hook-shaped, as shown best in Figs. 2 and 3 of the drawings. 75 In service, the heel and toe rest upon the spring 20, to be locked thereby in the position shown in Fig. 2, with the hooked ends of the fingers turned toward each other and to the middle of the frame 17. When the 80 fingers are moved to the position shown in Fig. 3 of the drawings, the hooked ends are extended away from the frame, and in substantially perpendicular relation thereto. In this position, they are held by the spring 85 20, the toes 22 of said fingers passing the perpendicular between the spring 20 and the pins 16.

To provide the mop with a nether rubbing surface, I add the mat 23. The mat 23 90 is preferably constructed of felt or other soft, thick material, the purpose being that if in service the fibers of the ring 13 be mashed down and displaced to expose the bottom of the mitt, a rubbing surface such 95 as the mat 23 will then be presented to the surface being treated.

In the usual employment for which the mop is designed, a handle 24 is employed. This handle may be of any desired construction, and may be united to the block 9 in any preferred way. As shown in the drawings, the block is furnished with an inclined orifice 25, and the handle 24 is fur-

nished with a tapered end 26, which is forced within said orifice. The upper cover of the mitt 10 is correspondingly provided with a hole 27, which in service registers with the opening of the orifice 25.

Operation.—With a mop constructed and arranged as described, the block 9 is preliminarily inserted within the pocket of the mitt 10. The free ends of the girdle 12 and ring 13 are spread, as best seen in Fig. 4 of the drawings, and the fingers 15 are opened to the position shown in Fig. 3 of the drawings. The girdle ends are now drawn over the fingers 15, and the eyelets 14 formed in said girdle are adjusted over the ends of said fingers. The girdle ends now containing the fingers 15 are forced over to substantially parallel relation with the frame 17. In this movement, the fingers are forced to the position shown in Fig. 2 of the drawings. The toes 22 thereafter serve to press the free ends of the fingers 15 upon the ends of the girdle, and to hold said ends in juxtaposed relation. The handle 24 is now inserted through the hole 27 and forced within the orifice 25. The mop is now in position for service.

The girdle 12, is packed to form a surrounding protective buffer or pad for the block 9. The presence of the girdle or protective buffer formed thereby avoids marring the standing trim of a room, or the furniture contained therein. It will also be observed that, as above indicated, if the pressure applied to the mop displaces the fibers of the ring 13, the mat 23 provides a protective and polishing surface at this point.

When it is desired to wash or clean the mop, the operator draws outward and apart the ends of the girdle 12, and by so doing rocks the fingers 15 to the position where they are free of engagement with the girdle, such as that shown in Fig. 3 of the drawings. The block 9 is now withdrawn from the mitt 10, which, being composed entirely of fibrous material, is further immersed in water or other cleaning fluid and treated in the manner usual in washing or cleaning articles of analogous character.

While I have herein described the mop as used in conjunction with an elongated handle and a filling block, it will be understood that the handle and block may be omitted, and the hand of the operator in-

serted within the mitt, for the manipulation of the mop.

Claims:

1. A mop, comprising an open-ended mitt having a fringed ring-shaped edge; and a relatively thickened mat mounted in the nether surface of said mitt.

2. A mop, comprising an open-ended mitt having a fringed edge provided with free ends adapted to close said mitt; means for fastening said ends; a filling member for said mitt, having a handle socket; and a handle fitting said socket.

3. A mop, comprising an open-ended mitt having a fringed edge; a block to fill said mitt, said block being provided with an annular groove; a girdle about said block to fill said groove and extending beyond the edge thereof, said girdle being adapted to close the open end of said mitt to hold said block therein; and a handle engaging said block and extending through said mitt.

4. A mop, comprising an open-ended mitt; a girdle mounted within said mitt and provided with a fringed ring, said girdle having free end extensions adapted to overfold the open end of said mitt to close the same; a filling block for said mitt; and a plurality of hook-like fingers mounted on said block to engage and hold the ends of said girdle in service position.

5. A mop, comprising an open-ended mitt; a girdle mounted within said mitt and provided with a fringed ring, said girdle having free end extensions adapted to overfold the open end of said mitt to close the same; a filling block for said mitt; a plurality of hook-like fingers mounted on said block to engage and hold the ends of said girdle in service position; and spring locking means for holding said fingers in holding relation to said girdle.

6. A mop, comprising a full-sided, hollow mitt having a pendent, fringed edge, a padded, encircling edge, and a relatively thickened mat mounted on the nether surface thereof, said mat being constructed from washable materials.

In testimony whereof I have signed my name to this specification in the presence of two subscribing witnesses.

CHARLES F. J. DUPUY.
